UNITED STATES PATENT OFFICE.

JOHN SULLIVAN, OF SUFFIELD, CONNECTICUT.

TOBACCO-HOIST.

SPECIFICATION forming part of Letters Patent No. 739,358, dated September 22, 1903.

Application filed August 12, 1902. Serial No. 119,422. (No model.)

To all whom it may concern:

Be it known that I, JOHN SULLIVAN, a citizen of the United States of America, residing at Suffield, in the county of Hartford and 5 State of Connecticut, have invented certain new and useful Improvements in Tobacco-Hoists, of which the following is a specification.

Tobacco while curing is hung in tiers in 10 huge sheds or barns, and considerable handling is necessary to get it into place.

The object of my invention is to provide a hoist by which the tobacco can be raised from the ground floor up to the upper parts of the 15 building with great ease and little liability of bruising or marring the leaves.

In the drawings, Figure 1 is a cross-sectional view of a curing-shed and shows my hoist in place. Fig. 2 is a detail side view of 20 the hoist. Fig. 3 is a detail front view.

In the drawings, A denotes bars or girders arranged crosswise of the building in tiers one above the other.

B denotes stringers running lengthwise of 25 the building.

In the drawings the tobacco is shown as being cured on the stalk, these stalks being secured to a lath C. This lath C is long enough so that its ends will rest on the stringers B, 30 as shown at D in Fig. 1. In filling the upper tiers of a building it has been customary to station a man on each tier and have him take the lath from the man below him and pass it to the man above him. I have found that by 35 this method many of the leaves are bruised or scratched, so that the leaves after curing are marred and defective, occasioning considerable loss to the grower. In order to handle these laths with the stalks attached to 40 them, so that the leaves will not become damaged, I have devised the herein-described hoist. It consists of the bar a, which supports by a swivel connection b the frame c, in which is mounted the shaft d, on which are

the sheaves e, over these sheaves running the 45 ropes f, made up of sections joined as at g. Connecting these ropes are the slats h, which carry hooks k, which are adapted to receive and hold the laths C, as clearly shown in Fig. 3. A brake M, made up of a bar m, pivotally 50 supported from the frame c by the arms n, is adapted to engage the slats h to prevent a backward movement of the ropes.

The operation of the device is readily understood. The bar a, which supports the 55 hoist, is of such length that its ends will rest upon the stringers B and is not secured to these stringers, but simply rests thereon, so that it may be moved lengthwise or crosswise of the building and from one tier to another. 60 The upper tiers are filled first, and as the workmen proceed from an upper tier to the next lower one the hoist is lowered one tier and a section of the rope taken out.

If desired, extra slats may be placed intermediate of the slats carrying the hooks, which may be used to operate the hoist.

I am aware that alterations of this arrangement may be made without departing from the spirit of my invention, and I desire to include herein any and all such modifications. 70

I claim as my invention—

In a device of the character described the combination of a supporting-bar, a frame, swiveled means for connecting said frame and 75 supporting-bar, a shaft mounted in said frame, carrying sheaves, sectional ropes fastened over said sheaves, slats connecting said ropes, hook members carried by said slats and pivotal means supported upon said frame adapted to lock ropes in position.

In testimony whereof I affix my signature in presence of two witnesses.

JOHN SULLIVAN.
